DESIGN FOR AN AIR VALVE CASING

Frederic A. Leisen, Grosse Pointe, Mich., assignor
to Detroit Lubricator Company, Detroit, Mich.,
a corporation of Michigan

Application July 10, 1941, Serial No. 102,011

Term of patent 14 years

To all whom it may concern:

Be it known that I, Frederic A. Leisen, a citizen of the United States and residing in the city of Grosse Pointe, county of Wayne, and State of Michigan, have invented a new, original, and ornamental Design for an Air Valve Casing, of which the following is a specification, reference being had to the accompanying drawing, forming part thereof.

Figure 1 is a view in perspective of an air valve casing showing my new design;

Fig. 2 is a top plan view of the casing, and
Fig. 3 is a view in side elevation thereof.

I claim:

The ornamental design for an air valve casing,
substantially as shown.

FREDERIC A. LEISEN.
